HEATER FOR A DIFFUSION PUMP

Donald L. Stevenson, Albion, and John L. Gallagher, Rochester, N.Y., assignors, by mesne assignments, to Consolidated Vacuum Corporation, Rochester, N.Y., a corporation of New York

Filed Apr. 16, 1959, Ser. No. 806,924

8 Claims. (Cl. 230—101)

This invention relates to diffusion type vacuum pumps, and more particularly is concerned with improved heater apparatus for such pumps.

Diffusion pumps for operation at high vacuums are well known. Such pumps operate on the principle that a liquid having relatively heavy molecules is vaporized in the pump by raising its temperature. The vapor with its heavy molecules is directed by suitable nozzles in a direction away from the region to be evacuated, towards a mechanical forepump. The accelerated molecules of vapor compress against molecules ahead of the nozzle, forcing them toward the mechanical forepump and thereby reducing the pressure within the evacuated region. The vapors are recondensed on a cool wall of the pump where the liquid is permitted to return to the bottom of the pump to be reheated and vaporized.

It has been the general practice heretofore to provide a reservoir of oil, for example, at the bottom of the diffusion pump and to apply heat to the bottom of the diffusion pump by means of a flat electric heater attached to the bottom of the pump. The heat is transferred to the oil by conduction through the bottom wall of the pump. Thus the oil is caused to boil, producing vapors which rise in the pump wherein they are directed through orifices which produce the proper jets of heavy molecule vapors of the oil. In addition to being an inefficient means of transferring heat to the pump liquid, such known heating methods do not cause the liquid to boil uniformly. Local hot spots exist which produce greater boiling activity in certain portions of the liquid. The liquid does not release the vapors in a steady fashion. The result is erratic and inefficient operation of the pump.

In copending application Serial No. 649,890, filed April 1, 1957, under the names of George H. Bancroft, Gordon Gerow, and Donald Stevenson, and assigned to the same assignee as the present invention, there is described an improved heating means for a diffusion pump which supplies heat more uniformly through the volume of the liquid. The heater therein described includes a centrally positioned cartridge type heater which projects up through the bottom of the pump, with fins attached thereto to distribute the heat through the liquid. The vapors are heated additionally after they leave the surface of the liquid by the heating fins which project upwardly above the liquid surface.

The present invention provides an improved heater for a diffusion pump which increases the turbulence of the liquid and greatly increases the energy with which the vapor is discharged from the liquid surface and sent up the central stack of the nozzle assembly. The present invention is particularly applicable to large capacity pumps where a large volume of oil vapor must be continuously generated at higher temperatures and higher boiler pressures.

In brief, the present invention provides a diffusion pump in which at least one, but preferably a plurality of, cartridge-type heating elements project upwardly from

2

the bottom and are provided with radially extending fins projecting outwardly from the heating elements both below and above the surface of the liquid charge in the bottom of the pump. Each of the finned heating elements is surrounded by a hollow cylindrical member which projects upwardly from the bottom of the pump above the surface of the liquid. The cylindrical members localize the heating of the liquid, causing strong convection currents, both in the liquid and in the vapor rising above the surface thereof. The result is greater agitation of the surface of the liquid, giving rise to a more uniform and continuous discharge of vapor, and greater velocity of the vapor molecules in the nozzle stack, giving rise to increased pumping speed and efficiency.

For a better understanding of the invention, reference should be had to the accompanying drawings, wherein:

Fig. 1 is a side elevational view, partially in section, 20 of a diffusion pump incorporating the improved heater of the present invention;

Fig. 2 is a sectional view taken substantially on the line 2—2 of Fig. 1;

Fig. 3 is a fragmentary sectional view of a modified 25 form of the heater;

Fig. 4 is a sectional view taken substantially on the line 4—4 of Fig. 3;

Fig. 5 is a fragmentary sectional view of a further 30 modification of the heater; and

Fig. 6 is a sectional view taken substantially on the line 6—6 of Fig. 5.

Referring to the form of the invention as shown in Figs. 1 and 2, the numeral 10 indicates generally the housing of the diffusion pump which includes a hollow 35 cylindrical portion with a press-formed bottom wall 14. The bottom wall 14 is brazed, welded, or otherwise secured to the bottom edge of the hollow cylindrical portion 12 to provide an hermetic seal therebetween. The center portion of the bottom wall is raised to form an 40 annular recess 15 with the cylindrical wall portion 12 around the inside of the joint between the bottom wall and the side wall.

The upper end of the pump is provided with a suitable 45 flange 18 to which a cooperating flange forming a part of the system being evacuated may be secured. The inlet to the pump is provided by a centrally located opening through the flange 18 communicating with the interior of the housing 10.

The interior of the pump includes a suitable nozzle 50 assembly, indicated generally at 20. The nozzle assembly may be of conventional design comprising a hollow central sectional nozzle stack having overlapping sections forming annular downwardly-directed orifices, such as indicated at 22, 24, and 26. Vapors rising in the center 55 stack of the nozzle assembly 20 are directed out of the respective orifices in downwardly directed nozzles. The lower cylindrical end 28 of the nozzle assembly 20 is secured to and supported by a vapor-confining member 30 which extends outwardly substantially to the outer 60 cylindrical wall 12 and then downwardly to the bottom wall 14, the vapor-confining member at its lower edge rests in the annular recess 15. Openings 32 are provided around the lower edge of the vapor-confining member to permit the flow of condensed oil vapors to return to 65 the pool of liquid in the bottom of the pump. The level of oil in the bottom of the pump is indicated by the dotted line 34.

An internal condensing wall, such as formed by a 70 tapered metal sleeve 36, is secured at its upper end to the flange 18. The vapors directed downwardly out of the nozzle orifices hit the condensing wall and condense into oil droplets which run down to the vapor-confining

member 30 and then outwardly and downwardly to return to the oil charge. The condensing wall 36 may be cooled if desired by suitable cooling means such as water-cooling coils (not shown) wrapped around the condensing wall 36.

The heater assembly to which the present invention is particularly directed is located in the lower end of the housing 10 for heating the liquid charge therein and generating vapors for operation of the pump nozzles. In the form of the invention shown in Figs. 1 and 2, the bottom wall 14 is provided with a pair of cup-shaped cylindrical recesses 38 and 40. Hollow casings, such as those indicated at 42 and 44, project upwardly in the recesses 38 and 40, the hollow casings being closed off at their upper ends and being hermetically sealed to the bottom wall 14 where they project through the bottom of the recessed portions 38 and 40 thereof. Each of the casings 42 and 44 have secured thereto a plurality of radial fins 46 which project at their upper ends above the surface of the liquid.

Cartridge heaters 48 and 50 are positioned inside the hollow casings 42 and 44 respectively. Such type heaters are well known and may be obtained in a great range of sizes. The cartridge heaters include outer metallic walls which fit snugly inside the hollow casings to provide heat conduction between the cartridge heaters and the casings and associated fins. Leads for connecting the cartridge heaters to a suitable source of electrical power (not shown) are brought out of the bottom of the casings.

Each of the heaters is surrounded by a hollow cylindrical pipe, such as indicated at 52 and 54, which projects upwardly from the bottom of the recessed regions 38 and 40 in the bottom wall 14. The lower end of the pipes 52 and 54 are provided with openings 56 which permit free flow of oil into the interior regions of the pipes. The upper end of the pipes 52 are tapered to a smaller diameter and extend above the heater casing and associated fins. Additional centrally-positioned cylindrical members 58 and 60 are positioned above the heaters and are supported from the pipes 52 and 54 respectively, as by radial supports 62.

Figs. 3 and 4 show a modified form of the multiple heater arrangement described above in connection with Figs. 1 and 2. In this form of the invention the heaters are not recessed, but rather, the bottom wall 14' is made relatively flat. Casings 42' and 44' extend up through the flat bottom wall and are provided with radially extending fins, in the same manner as the heating arrangement of Figs. 1 and 2. The surrounding cylinders are provided by metallic cup-shaped members 64 and 66, with the bottoms of the cup-shaped members extending under the fins of the heaters. The sides in turn extend up and surround the fins of the respective heaters. The open tops of the cup-shaped members extend above the fluid level but do not extend above the tops of the heaters. Holes 67 permit fluid to flow into the members 64 and 66. This arrangement is easier and less expensive to construct than that of Fig. 1.

The use of pipes or cylindrical enclosures surrounding each of the heaters has been found most effective in multiple heater units. In multiple heating units without the cylindrical skirts it has been found, for example, that at high surface temperature of the heaters where they project above the fluid level, decomposition of the fluid results. However, with the addition of the skirts surrounding each of the heaters, the concentration of vapors within the direct vicinity of the heater causes the heat to be dissipated at a rate which prevents burning and decomposition of the fluid, and at the same time increases the pumping speed.

The improved heaters with the skirts have also been found to improve the operation of pumps using a single finned cartridge heater arrangement, by increasing turbulence through the formation of strong convection currents in the fluid. A single heater unit of this type is

shown in Figs. 5 and 6. The diffusion pump of Figs. 5 and 6 may be essentially identical to that described in the above-mentioned copending application in which the housing consists of an outer cylindrical wall 70 and an enclosing flat bottom wall 72. The heater casing 74 extends through the bottom wall 72 and is provided with a plurality of heat-conductive radially extending fins 76. The lower end of the jet element, indicated at 78, rests on the wall 72. The cartridge heater 78 extends up into the casing 74 and is secured into position by a set screw 80 extending through a collar 82 welded to the bottom wall 72. A cylindrical skirt 84 surrounds the heater with its fins 76, the cylindrical skirt 84 extending above the normal fluid level indicated by the dotted line 86. The cylindrical skirt 84 is provided with openings 88 adjacent the lower edge thereof through which the oil enters into the interior region of the skirt 84 adjacent the heater. This design also results in greater effective heating by reducing the amount of heat transferred to the outer wall of the pump and to the wall of the nozzle assembly.

The heater arrangement, whether in single or multiple units, permits greater watts input to be supplied to the pump without decomposition of the oil charge. The result is significantly faster pumping. The heater arrangement of the present invention has been found to produce violent agitation, providing better heat distribution through the liquid and preventing decomposition due to localized "hot spots."

What is claimed is:

1. A diffusion pump comprising an outer sealed housing having input and output conduit connections thereto, a hollow nozzle assembly positioned vertically in the housing and open at the lower end thereof; a liquid charge in the housing; and means for boiling the liquid to continuously generate vapor within the nozzle assembly including a plurality of hollow casings projecting upwardly through the liquid from the bottom of the housing, a plurality of heat conductive fins joined to each of the casings and projecting radially outwardly from the casings, the fins extending above the surface of the liquid, and a cartridge-type heater within each of the hollow casings; and a plurality of hollow cylindrical members, one of said members surrounding each of the casings and associated fins, the cylindrical members projecting above the liquid surface and being formed with an opening in the wall thereof below the surface.

2. Apparatus as defined in claim 1 wherein the cylindrical members each include two sections of different diameter, the uppermost section being of smaller diameter and concentrically supported from the larger diameter section.

3. A diffusion pump comprising an outer sealed housing having input and output conduit connections thereto, a hollow nozzle assembly positioned vertically in the housing and open at the lower end thereof; a liquid charge in the housing; and means for boiling the liquid to continuously generate vapor within the nozzle assembly including a plurality of hollow casings projecting upwardly through the liquid from the bottom of the housing, a plurality of heat conductive fins joined to each of the casings and projecting radially outwardly from the casings, the fins extending above the surface of the liquid, and heater means within each of the hollow casings; and a plurality of hollow cylindrical members, one of said members surrounding each of the casings and associated fins, the cylindrical members projecting above the liquid surface and being formed with an opening in the wall thereof below the surface.

4. In a diffusion pump having a sealed outer housing and a hollow nozzle assembly located in a vertical position within the housing, heater means for continuously producing a flow of vapor into the nozzle assembly from a liquid charge in the bottom of the housing, comprising a plurality of rod-like heaters projecting upwardly

from the bottom of the housing through the liquid, a plurality of outwardly extending heat-conductive fins secured to each of the heaters for distributing the heat throughout the liquid, and a plurality of hollow cylindrical members, one of said members surrounding each of the heaters and associated fins, the cylindrical members projecting above the surface of the liquid and being formed with an opening in the wall thereof below the surface.

5. Apparatus as defined in claim 4 wherein the cylindrical members each include two sections of different diameter, the uppermost section being of smaller diameter and being concentrically supported from the larger diameter section.

6. In a diffusion pump having a sealed outer housing and a hollow nozzle assembly located in a vertical position within the housing, heater means for continuously producing a flow of vapor into the nozzle assembly from a liquid charge in the bottom of the housing, comprising at least one heater element having a vertical wall projecting upwardly from the bottom of the housing through the liquid, a plurality of outwardly extending heat-conductive fins secured to the heater element for distributing the heat throughout the liquid, and a hollow cylindrical member surrounding the heater element and associated fins, the cylindrical member projecting above the surface of the liquid and being formed with an opening in the wall thereof below the surface.

7. In a diffusion pump having an outer housing and a hollow nozzle assembly located in a vertical position within the housing, heater means for continuously producing a flow of vapor into the nozzle assembly from a

5 liquid charge in the bottom of the housing, comprising at least one heater projecting upwardly from the bottom of the housing through the liquid, a plurality of outwardly extending heat-conductive fins secured to the heater for distributing the heat throughout the liquid, and a hollow cylindrical member surrounding the heater and associated fins, the cylindrical member projecting above the surface of the liquid and being formed with an opening in the wall thereof below the surface.

8. In a diffusion pump having an outer housing and a hollow nozzle assembly located in a vertical position within the housing, heater means for continuously producing a flow of vapor into the nozzle assembly from a liquid charge in the bottom of the housing, comprising a plurality of heater elements projecting vertically from the bottom of the housing into the region above the surface of the liquid, and confining cylindrical members surrounding each of the heater elements for confining the liquid and vapors around each of the heating elements, each of said cylindrical members being formed with an opening in the wall thereof below the surface.

liquid charge in the bottom of the housing, comprising at least one heater projecting upwardly from the bottom of the housing through the liquid, a plurality of outwardly extending heat-conductive fins secured to the heater for distributing the heat throughout the liquid, and a hollow cylindrical member surrounding the heater and associated fins, the cylindrical member projecting above the surface of the liquid and being formed with an opening in the wall thereof below the surface.

8. In a diffusion pump having an outer housing and a hollow nozzle assembly located in a vertical position within the housing, heater means for continuously producing a flow of vapor into the nozzle assembly from a liquid charge in the bottom of the housing, comprising a plurality of heater elements projecting vertically from the bottom of the housing into the region above the surface of the liquid, and confining cylindrical members surrounding each of the heater elements for confining the liquid and vapors around each of the heating elements, each of said cylindrical members being formed with an opening in the wall thereof below the surface.
